AIR CONDITIONING DEVICE

Jess Mitchell, St. Louis, Mo.

Application May 26, 1937, Serial No. 144,784

1 Claim. (Cl. 257—202)

My invention has relation to improvements in air conditioning apparatus and consists in the novel features of construction more fully set forth in the specification and pointed out in the claim.

5 The principal object of the invention is to provide a compact unitary device for cooling or heating and circulating the air within a room so as to either lower or raise the temperature of said room air.

10 It is a further object of the invention to provide such a device that may be manufactured at low cost and that may be readily moved from room to room as desired.

These advantages, as well as others inherent 15 in the invention, will be better apparent from a detailed description thereof in connection with the accompanying drawings, in which:

Figure 1 is a side elevation of my improved air 20 conditioning apparatus; Fig. 2 is an end elevation looking toward the open end from which the air discharges; Fig. 3 is a vertical transverse section taken on the line 3—3 of Fig. 1; Fig. 4 is a vertical longitudinal section through the apparatus taken on the line 4—4 of Fig. 2; Fig. 5 is a vertical cross 25 section taken on the line 5—5 of Fig. 1; Fig. 6 is a side elevation of a fragment of the apparatus showing a filter applied to the air inlet duct; and Fig. 7 is a longitudinal sectional detail taken on the line 7—7 of Fig. 6.

30 Referring to the drawings, 1 represents a cylindrical casing supported by feet 2, 2 on a suitable base 3 on which a motor M is also mounted. Concentrically disposed within the casing 1 there is a tube 4 of smaller diameter so as to leave an 35 annular space S between said tube 4 and the casing 1. The tube 4 stops short of a closure plate 5 disposed over the end of casing 1 adjacent to motor M so as to provide a space S' for a fan F securely fixed on the motor shaft 6. The blades 40 7 of the fan are flat but have their outer edges 8 and inner edges 9 arcuate so as to follow the contour of the casing 1 and tube 4, respectively. It will be observed (Figs. 1 and 4) that the inner edges 9 of the blades slightly overlap the adjacent 45 end of tube 4, and the blades are pitched so that upon being rotated in the proper direction, they will force air through the space S toward the open end thereof. The tube 4 is supported within the casing 1 by a plurality (four in the present 50 instance) of ducts 10 fixed at their inner ends in the wall of tube 4 and at their outer ends in the casing 1. The side of each duct toward the fan F is V-shaped so as to offer a minimum of resistance to the air that is forced through the 55 casing by the fan F. A cylindrical member 11

fits snugly within the tube 4 and is of a length so that it extends from the inner edges of the ducts 10 to an annular flange 12 formed on the inner end of tube 4. Member 11 has a diametrically disposed partition 13 running through it from end to end and a semicircular end wall 14 between said partition and the periphery of said member 11.

The partition 13 and end wall 14 form a container within the member 11 in which ice I, or other cooling medium, may be held. A cover plate 15 is provided for said container, between which and a cover plate 16 for the tube 4 there is disposed a coil spring 17 to take up any play between the parts so as to eliminate vibration 15 when the motor M and fan F are operating. When the apparatus is used as an air cooler, the ice container formed within the member 11 is disposed at the top of the tube 4; but if it is desired to use the apparatus as an air heater, 20 this container may be inverted and a suitable heating element (not shown) disposed either within it or on the partition 13.

The operation of my improved air conditioning apparatus is as follows:

We will assume that the container of the member 11 is charged with ice so that the apparatus may be used as an air circulating device. The motor M is now started so as to rapidly rotate the fan F, the blades of which will force air outwardly through the space S into the room and draw the room air through the ducts 10 into the member 11 below the partition 13. As the air travels through the member 11, it will, of course, be cooled by contact with the cool surfaces of the 35 member 11 through which the air is moved by the action of the fan F. Thus, we have a continuous circulation of air through the ducts 10, through the member 11, and back through the space S within the casing 1 from which the cooled 40 air is discharged into the room.

The cover plate 5 is removable, for which purpose I provide a radially disposed tapering opening 18 leading from the center thereof to the periphery of the plate 5. This opening 18 permits the cover plate to be disposed over the shaft 6 of the motor, after which a sliding gate 19 may be slipped into the opening and held in place by guide lugs 20, 20, as well understood in the art.

A plurality of spring clips 21, 21 may be secured 45 adjacent to the inner end of the casing 1 for the purpose of engaging and holding in place the cover plate 5.

Referring to Figs. 6 and 7, 22 is an air pervious screen held in place on the end of the duct 10 55

by a spring holder 23 shaped to fit the outline of the duct 10.

Having described my invention, I claim:

5 An air conditioning apparatus comprising a cylindrical casing closed at one end, a tube disposed concentrically within the casing and spaced from the walls thereof, one end of said tube being spaced from the closed end of the casing and having an air outlet and the opposite end of the

tube being closed and having air inlet ducts leading through the casing wall, an air conditioning device removably disposed within said tube, and a fan in the space between the tube and the closed end of the casing, said fan having blades operating between the cylindrical walls of the casing and of the tube. 5

JESS MITCHELL.
